WIRE GRIPPING MECHANISM

Leo D. Mersek, Euclid, Ohio, assignor to The Ajax Manufacturing Company, Euclid, Ohio, a corporation of Ohio

Application July 2, 1953, Serial No. 365,611

7 Claims. (Cl. 279—1)

This invention relates to grip mechanisms for gripping wire, or the like, as for example, in conjunction with wire drawing and/or feeding operations being performed in advance of a cold-header or other fabricating machine to which the wire is being supplied.

In order to properly determine the length of wire stock to be operated upon by the header, it has heretofore been necessary to provide the header with feed rolls and a feed stop. It has also been necessary to take precautions to see that the wire is abutted and held against the feed stop by an overfeeding action of the feed rolls, for each cutoff or forming operation being performed by the header. The novel grip mechanism of the present invention not only eliminates the need for such a feed stop when feeding the wire by means of feed rolls, but also permits the use of a positive feed mechanism such as a so-called chisel type of feed frequently used in nail making machines. Such chisel type of feed and various other forms of feeds have been found objectionable as tending to mar the wire when the latter is subjected to any pull-back movement. As will be apparent hereinafter, the novel grip mechanism of this invention prevents any pull-back movement of the wire, and hence, removes the objection previously raised against these various forms of feeds.

This novel grip mechanism also accommodates a plurality of separate strands of wire rather than the single strand to which previous grip mechanisms have been limited.

In previous grip mechanisms embodying tapered grip blocks, at least a small amount of pull-back movement of the wire for rendering the grip blocks effective has been unavoidable and this pull-back movement has made it difficult to obtain an accurate and satisfactory feeding of the wire except by an overfeeding of the wire against a feed stop by means of feed rolls. Since the grip mechanism of this invention eliminates all such pull-back movement, it eliminates the feeding inaccuracies and other objections incident thereto, as well as the longitudinal shifting of the grip blocks which heretofore occurred as a part of such pull-back movement.

As one of its objects, this invention provides novel grip mechanism for gripping wire, or the like, in either single or multiple strands and which has a positive actuation such that the gripping and releasing of the wire can be accurately timed in relation to drawing and/or feeding operations being performed on the wire, such as the drawing and feeding operations performed in conjunction with a wire drawer used in advance of a cold-header.

Another object is to provide grip mechanism of this kind in which a relative closing movement between co-operating grip blocks is produced by the camming action of a wedge member associated with the grip blocks and to which wedge member a positive actuation is imparted, the grip blocks having a limited lateral relative shifting in gripping or releasing the wire but being substantially held against any longitudinal shifting.

Still another object is to provide such a grip mecha-

2

nism in which the grip blocks are located in a grip box and constitute a group, preferably of three or more grip blocks, for gripping two or more strands of wire and in which the wedge member is movable in the grip box between such group and an adjacent abutment means.

It is likewise an object of this invention to provide a novel grip mechanism in which the elimination of the longitudinal shifting of the grip blocks leaves the gripping and releasing actions to be determined only by the limited lateral relative shifting of the grip blocks such that by maintaining the lateral movement at a minimum, a small wedge angle is feasible and will produce a heavy gripping pressure in response to a relatively small actuating force, such as the pressure of a relatively light setting spring, applied to the movable wedge member.

A further object is to provide a grip mechanism of the character indicated above in which spring means effective on the wedge member through either a pulling or pushing force tends to move the wedge member in a direction to produce the relative closing movement of the grip blocks, and in which actuating means operable to move the wedge member in the opposite or grip-releasing direction becomes effective after the closing of an intervening clearance space.

As another of its objects, this invention provides novel grip mechanism of the kind above referred to which is cyclically operable and in which the wedge actuating means is cam-operated, preferably by cam means associated with the driving means for the wire drawer.

Additionally, this invention provides novel grip mechanism of this kind in which the wedge member is servomotor actuated.

The invention can be further briefly summarized as consisting in certain novel combinations and arrangements of parts hereinafter described and particularly set out in the claims hereof.

In the accompanying sheets of drawings, forming a part of this specification:

Fig. 1 is a partial plan view showing the novel grip mechanism being used with a wire drawer;

Fig. 2 is a partial side elevation of the grip mechanism and wire drawer;

Fig. 3 is a plan view of the grip mechanism of Fig. 1 but on a larger scale;

Fig. 4 is an end view of the grip mechanism and wire drawer;

Fig. 5 is a vertical longitudinal section taken through the grip mechanism on section line 5—5 of Figs. 1 and 3;

Fig. 6 is a transverse vertical section taken through the grip mechanism as indicated by the section line 6—6 of Figs. 1 and 3;

Fig. 7 is a partial plan view showing a modified construction in which another form of actuating means is provided for the grip mechanism and in which the grip mechanism is being used with a wire drawer;

Fig. 8 is mainly a side elevation of the grip mechanism and wire drawer of Fig. 7;

Fig. 9 is a partial longitudinal vertical section taken through the grip mechanism of Figs. 7 and 8, the view being taken substantially as indicated by section line 9—9 of Fig. 7;

Fig. 10 is a partial side elevation with certain portions broken away, showing the novel grip mechanism as being servomotor actuated and as being used with a wire drawer;

Fig. 11 is a partial plan view showing actuating means for the wire drawer and also showing limit switch means for controlling the servomotor;

Fig. 12 is a vertical section taken on section line 12—12 of Fig. 11; and

Fig. 13 is a further modification showing a group of

grip blocks in detached relation and adapted to grip a larger number of wires.

In Figs. 1 to 6 inclusive, the novel grip mechanism 10 is shown as being used in conjunction with a wire drawer 11 and as operating on a plurality of independent strands of wire, in this instance, two such strands 12 and 13. Although the grip mechanism 10 is here shown as operating on two strands of wire, this mechanism is also readily adaptable for operation on a single strand of wire or on more than two strands, as will be more fully explained hereinafter.

The wire drawer 11 is more fully disclosed in earlier Patent 2,226,400, granted December 24, 1940. For purposes of the present disclosure, it is sufficient to explain that the wire drawer 11 is of the reciprocating type comprising a frame 14 and a die box 15 reciprocably movable in the frame and carrying suitable die means 16 for performing successive drawing strokes on the wire. The drawing strokes are produced by movement of the die box 15 in a direction away from the grip mechanism 10 by means of a swinging draw lever 17.

The return movement or idle stroke of the die box 15 is in a direction toward the grip mechanism 10 and it is during this return movement of the die box that the wires 12 and 13 are advanced through the grip mechanism in the direction indicated by the arrow 18 and are supplied to the cold-header by the feed rolls of the latter. The return movement of the die box 15 is assisted by return spring means 19 engaging this die box and takes place during the forward feeding of the wire. The draw lever 17 is rockably supported in the frame 14 by transverse pivot means 20 and swinging movement is imparted to the draw lever by the rotation of an actuating shaft 21 which is suitably driven and which carries a crankpin or eccentric 22 with which the lower end of the draw lever is connected by the connecting rod 23.

The grip mechanism 10, as used in conjunction with the wire drawer 11, serves to hold the wires 12 and 13 against backward movement during the drawing stroke of the die box 15, that is to say, against backward movement while the die means 16 is being pushed over the wires to perform the drawing stroke thereon. The grip mechanism 10 permits a free forward movement of the wires 12 and 13 therethrough while the drawn wire is being fed to the header, but when the desired amount of forward feeding of the wire has taken place, the grip mechanism grips the wires and maintains its grip on the wires during the succeeding drawing stroke of the die box 15. Upon the completion of the drawing stroke of the die box, the grip mechanism 10 is actuated to release its grip on the wires to permit the subsequent feeding of the drawn wires to the header. The grip mechanism 10, as used in conjunction with the reciprocating wire drawer 11, thus has a sequential or cyclical operation in timed relation to the reciprocating drawing and return strokes of the die box.

As shown in the drawings, the grip mechanism 10 comprises a grip box 25 which is suitably mounted on the frame 14 of the wire drawer 11 and which has pairs of opposed side walls 26, 27 and 28, 29 defining a grip chamber 30. The grip mechanism 10 also comprises a plurality of grip blocks disposed in grouped cooperating relation in the chamber 30 and which, in this instance, consist of side blocks 31 and 32 and an intermediate block 33. In the grip mechanism here shown, the three grip blocks 31, 32 and 33 are employed for gripping the two strands of wire 12 and 13, but in other applications of the present invention in which a single strand of wire is to be gripped, only two grip blocks would be needed and in that case, the intermediate grip blocks 33 would be omitted. Likewise, in a situation where three or more strands of wire are to be gripped, corresponding additional intermediate blocks would be used between the side blocks 31 and 32, the number of such intermediate blocks depending upon the number of strands of wire

and always being one less than the number of such strands. Fig. 13 shows such a modified construction in which three of the intermediate grip blocks 33 are provided between the side blocks 31 and 32 for gripping four wires.

The grip blocks 31 and 33 constitute one pair of such blocks which serve the wire 12, and the grip blocks 32 and 33 constitute a second pair of such blocks which serve the wire 13. The intermediate block 33 is thus common to both of these pairs of blocks inasmuch as the intermediate block serves both of the wires 12 and 13. The grip blocks 31 and 33 have adjacent cooperating complementary grip elements 34 and 35 thereon which grip the wire 12 in response to a lateral or transverse relative closing movement between these blocks. In this instance, the cooperating grip elements 34 and 35 are grooves or partial grooves formed in the adjacent faces of the blocks 31 and 33 and define a grip passage 36 through which the wire 12 extends.

Similarly, the grip blocks 32 and 33 have cooperating complementary grip elements 37 and 38 thereon which grip the wire 13 in response to a lateral or transverse relative closing movement between these blocks. The grip elements 37 and 38 are, likewise, in the form of grooves or partial grooves formed in the adjacent faces of the blocks 32 and 33 and which define a grip passage 39 through which the wire 13 extends.

The side walls 26 and 27 of the grip box 25 constitute abutment walls between which the group of grip blocks is located. Abutment members 40 and 41 are located in the grip box and lie against the side walls 26 and 27 thereof. The abutment member 40 is engaged directly by the outer side face 42 of the side block 31, and the outer side face 43 of the side block 32 is presented toward the abutment member 41 but is spaced therefrom by an intervening space 44 of substantial width. The side block 31 is of a substantially straight or regular shape having substantially parallel side faces, but the side block 32 is a wedge-shaped block whose outer side face 43 forms a bearing surface which extends in a relatively inclined relation to the feed and drawing axes 12^a and 13^a of the wires 12 and 13. A bearing plate 45 lying against the abutment member 41 has a substantially flat bearing surface 46 which is in substantially parallel relation with the feed and drawing axes 12^a and 13^a and faces toward the inclined side face 43 of the grip block 32.

The grip blocks 31, 32 and 33 have substantially no longitudinal movement in the grip box 25, inasmuch as these grip blocks are of a length which is only slightly less than the distance between the adjacent faces of the walls 28 and 29, and are firmly held against the wall 29 by the action of a compression spring 47 on these blocks. The spring is seated in a threaded hollow plug 47^a and its compression can be varied by screwing the plug inwardly or outwardly of a threaded opening in which it is mounted.

The relative closing lateral or transverse movement which renders the grip passages 36 and 39 effective on the wires 12 and 13, is produced by longitudinal movement of a wedge member 48 in the grip box 25 in the intervening space 44 between the side block 32 and the gearing plate 45. As shown in the drawings, the space 44 defines a tapered guideway extending substantially parallel to the grip passages and in which guideway the wedge member 48 is reciprocably movable. The wedge member 48 is here shown as having a straight, flat bearing surface 49 on one side thereof which is presented toward the bearing surface 46 of the bearing plate 45, and on the opposite side thereof, has a relatively inclined bearing surface 50 which is presented toward the inclined bearing surface 43 of the side block 32.

The wedge member 48 can be used with the bearing surfaces 49 and 50 thereof in direct sliding engagement with the bearing surfaces 46 and 43, but preferably and as here shown, antifriction bearing units 51 and 52 are

provided between these pairs of bearing surfaces. The bearing unit 51 comprises suitable cage means 53 and a longitudinal row of rollers 54 retained in such cage means and disposed between the pair of inclined bearing surfaces 43 and 50. The bearing unit 52 similarly comprises suitable cage means 55 and a row of rollers 56 retained in the cage means and disposed between the pair of straight bearing surfaces 46 and 49.

The grip box 25 is provided at the bottom of the chamber 30 with a bottom bearing plate 57 on which the grip blocks 31, 32 and 33, and the wedge member 48 are slidably supported. The bottom plate 57 also supports the bearing units 51 and 52, the bearing plate 45 and the abutment members 40 and 41. Screws 58 and 59 engaged in the abutment members 40 and 41 provide a lifting means for these members by which their removal from the grip box is facilitated. The grip box 25, with the above-described grip mechanism components assembled therein is secured to the frame 14 of the wire drawer by suitable bolts 60.

When longitudinal movement is imparted to the wedge member 48 in the direction of the advance movement of the wires 12 and 13, this wedge member exerts a spreading action between the bearing surface 46 and the inclined bearing surface 43 of the side block 32 which results in a compressive force being applied to the group of grip blocks transversely thereof between the inclined bearing surface 50 and the abutment member 40. This compressive force causes relative closing movement between the adjacent blocks of the group to produce the above-mentioned gripping action of the grip passages 36 and 39 on the wires 12 and 13. Longitudinal movement of the wedge member 48 in the opposite direction causes this compressive force on the block group to be relieved, whereupon compression springs 61 and 62 embodied in the block group cause relative separating or expanding movement between the adjacent blocks for releasing the gripping engagement on the wires 12 and 13.

Shifting or chattering of the bearing units 51 and 52 in the grip box 25 is prevented during these movements of the wedge member 48, preferably by means of tension springs 63 and 64. These tension springs are located in longitudinal openings 65 of the side wall 29 of the grip box, and are provided at one end thereof with hook elements 66 by which they are connected with the respective bearing units 51 and 52. At the opposite end thereof, the tension springs 63 and 64 are provided with hook elements 67 which are connected with anchor pins 68 supported by the side wall 29 of the grip box.

The above-mentioned longitudinal movements of the wedge member 48 are imparted thereto through stem means connected with this wedge member and projecting from the grip box 25. In this instance, the stem means comprises a stem 70 formed by a rod slidably extending through an opening 71 of the side wall 28 and having its inner end anchored to the wedge member by a threaded connection and by a transverse locking pin 72. The outer end of the stem 70 carries an adjustably mounted collar 73 through which the actuating thrust for the wedge member 48 is imparted to this stem.

The collar 73 is here shown as comprising a block 73^a having an axial recess 74 in the end thereof facing toward the grip box 25. The recessed end of the collar 73 is provided with a substantially radially projecting annular flange 75 and the opposite end of the collar is provided with a threaded axial opening 76 which communicates with the recess 74. The collar 73 is mounted on the outer end of the stem 70 by means of an externally and internally threaded bushing 77. The external thread of this bushing engages in the threaded opening 76 of the collar and the internal thread of this bushing engages the threaded outer end 70^a of the stem 70.

The longitudinal movement of the wedge member 48 in the wire gripping direction is produced by a compression spring 78 located in surrounding relation to the stem

70 and disposed between the side wall 28 of the grip box and a spring seat 79 formed on or carried by the inner end of the bushing 77. One end of the spring 78 is received in a recess 80 of the wall 28, and the other end of the spring extends into the recess 74 of the collar 73. The expansive force of the spring 78 exerts an outward pull on the stem 70, such that the wedge member 48 is constantly being urged in a direction to cause gripping engagement of the blocks with the wires 12 and 13.

- 10 The movement of the wedge member 48 in the opposite or grip-releasing direction is produced by actuating means cooperating with the collar 73 and which, in this instance, includes an upright lever 81 swingably mounted in a bracket 82 of the frame 14 by a pivot pin 83. The 15 upper end of the lever 81 is a forked portion 84 which straddles the block 73^a of the collar 73 and is normally spaced from the flange 75 by an intervening clearance space 85. The lower end of the lever 81 carries a cam follower in the form of a roller 86 which engages a 20 rotary cam 87 mounted on the actuating shaft 21. The cam 87 is provided with a lift portion 88 and with high and low dwell portions 88^a and 88^b of a predetermined angular extent in relation to the desired actuation of the die box 15 by the draw lever 17.
- 25 The roller 86 is maintained in engagement with the cam 87 by a compression spring 89 disposed between the upper portion of the lever 81 and the frame 14. The outer end of this spring is received in a hollow spring seat 90 which is in the form of a screw plug engaged in a threaded opening 91 of the lever. The compression of the spring 89 can be varied as desired by adjustment of the plug 90 in the threaded opening 91.

The compression spring 89 also serves to maintain the clearance space 85 between the forked portion 84 of the lever 81 and the flange 75 of the collar 73. The presence of this clearance space 85 is important because it permits the compression spring 78 to move the wedge member 48 to the full extent necessary to produce an effective gripping of the wires 12 and 13 by the grip blocks. During

30 the grip-releasing actuation of the wedge member 48, the lever 81 is swung through an initial distance sufficient to take up the clearance space 85 before this lever becomes effective on the collar 73 for producing the grip-releasing movement of the wedge member.

35 The compression of the spring 78 and the width of the clearance space 85 can be adjusted as desired by shifting the bushing 77 in the threaded opening 76 of the collar 73. To facilitate the making of this adjustment, the outer end of the bushing 77 is provided with a square portion 92 to which a wrench, or the like, can be conveniently applied. The bushing 77 can be locked in its position of desired adjustment by means of a locknut 93 provided thereon.

40 From the construction of the grip mechanism 10 and its relation to the wire drawer 11, as above described, it will be seen that clockwise rotation of the actuating shaft 21 will be effective through the crankpin 22 and the connecting rod 23 to produce successive drawing strokes of the die box 15 by the draw lever 17. This clockwise rotation of the actuating shaft 21 will also bring the lift portion 88 of the cam 87 into engagement with the roller 86 to thereby cause a clockwise swinging of the lever 81 by which the gripping engagement of the grip blocks with the wires 12 and 13 is released to permit the forward

45 feeding of these wires following each such drawing stroke of the die box. During the time that the roller 86 is in engagement with the high dwell portion 88^a of the cam 87, the wedge member 48 will be maintained in its grip-releasing position. When the high cam portion 88^a is disengaged from the cam follower 86, the spring 89 causes a counterclockwise swinging of the lever 81, thereby releasing the pressure of the forked portion 84 on the collar 73 and permitting the compression spring 78 to produce movement of the wedge member in the wire gripping direction.

Figs. 7, 8 and 9 of the drawings show a grip mechanism 95 being used with a wire drawer 96 which is of the same type and general construction as the wire drawer 11. The grip mechanism 95 is generally similar to the grip mechanism 10 and functions in a similar manner, but employs a wedge member 97 which is actuated by a pushing force transmitted through the stem 98 for producing a gripping action of the grip blocks on the wires 12 and 13. The wedge member 97 and the adjacent grip block 99 have inclined bearing surfaces 100 and 101 which are reversed as compared with the direction of inclination of the corresponding bearing surfaces 43 and 50 of the wedge member 48 of the grip mechanism 10. In this modified grip mechanism 95, the bearing units 102 and 103 serve the same purpose as the bearing units 51 and 52 of the grip mechanism 10, but are held against chattering or endwise movement in the grip box by plungers 104 which are projected into the chamber of the grip box by compression springs 105.

Actuating movement for the wedge member 97 in a direction to produce a wire gripping action by the grip blocks is transmitted to the wedge member from the cam 87 of the wire drawer through linkage which includes a pair of upper and lower swingable levers 106 and 107. These levers have their adjacent ends 106^a and 107^a in overlapping relation and separated by an intervening clearance space 108 corresponding with the clearance space 85 of the grip mechanism 10. The outer end of the stem 98 of the wedge member 97 is provided with a yoke portion 109 which is located adjacent a yoke portion 110 provided on the upper end of the upper lever 106. The yoke portions 109 and 110 are flexibly connected by means of a thrust link 111 extending therebetween.

The upper lever 106 is swingably mounted in a bracket 112 on the frame of the wire drawer 96 by means of a transverse pivot pin 113. The lower lever 107 is swingably mounted in a bracket 114 by means of a transverse pivot pin 115, and its lower end is provided with a roller 116 forming a cam follower in engagement with the cam 87.

During the time that the roller 116 is in engagement with the low portion 88^b of the cam 87, the position of the lower lever 107 will be such that the clearance space 108 will be maintained and the lower lever will then have no effect on the upper lever 106. The roller 116 is maintained in engagement with the cam 87 by the force of a compression spring 117 applied to the upper end of the lower lever 107. While the clearance space 108 is maintained, the wedge member 97 will be constantly urged in a direction to produce gripping of the wires 12 and 13 by the force of a compression spring 118 applied to the lower end of the upper lever 106. The compression spring 118 has one end thereof in engagement with the lower end 106^a of the lever 106 and its other end received in the recess 119 of a screw plug 120 having adjustable engagement in an internally threaded opening 121 of a boss 122 provided on the frame of the wire drawer.

A pushpin 123 has one end thereof slidably extending through an opening 124 of the plug 120, and its other end slidably extending through an opening 125 of the lever portion 106^a. At an intermediate point thereof, the pushpin 123 is provided with a collar 126 forming a spring seat for the outer end of the compression spring 117. The outer end of the pushpin 123 is provided with a rounded portion which engages in a groove 127 of the lever portion 107^a.

From the arrangement and mounting of the compression springs 117 and 118, as just described above, it will be seen that the compression spring 117 will be effective on the upper end of the lower lever 107 through the pushpin 123 to constantly hold the roller 116 in engagement with the cam 87. It will also be seen that the compression spring 118 acts on the lower end of the upper lever 106 and constantly tends to move the wedge mem-

ber 97 in a wire gripping direction by a pushing force transmitted through the stem 98. Adjustment of the compression of the springs 117 and 118 and of the clearance space 108 can be readily produced by screwing the plug 120 inwardly or outwardly of the threaded opening 121 as by applying a wrench, or the like, to the hexagon-shaped integral projection 128 of this plug.

By the time that the drawing stroke of the die box 15 has been completed, the clockwise rotation of the cam 87 will bring the lift portion 88 of the cam in engagement with the roller 116 to thereby cause clockwise swinging of the lever 107, resulting in inward longitudinal movement of the pushpin 123 in the opening 124 of the plug 120. This clockwise swinging of the lever 107 takes up the clearance space 108, whereupon this lever engages and swings the lever 106 in opposition to the compression spring 118 to thereby apply a pulling force to the stem 98 by which the wedge member 97 is moved longitudinally in a grip-releasing direction.

Figs. 10, 11 and 12 show a grip mechanism 130 of substantially the same construction as the grip mechanism 95 and being used with a wire drawer 131 which is similar to the wire drawers 11 and 96, with the exception that the draw lever 17 is actuated by a drag link 132. The wedge member 97 of the grip mechanism 130 is actuated in its wire gripping and grip-releasing directions by servo-motor means, which is here shown as comprising a double acting pressure fluid cylinder device 133.

The drag link 132 of the wire drawer 131 has the outer end thereof connected with a swingable quadrant 134 which in turn is connected with a crankpin or eccentric 135 of a rotatable actuating shaft 136 by a connecting rod 137. The actuating shaft 136 is rotatably journaled in a bearing pedestal 138 which is maintained in fixed relation relative to the frame of the drawer 131 by stay rods 139.

The actuating shaft 136 is adapted to be driven from an available power take-off of the cold-header with which the wire drawer 131 is being used by means of a chain 40 140 extending around a sprocket 141 mounted on this shaft. A cam 142 mounted on the shaft 136 actuates a limit switch 143 in timed relation to the operation of the die box 15 of the wire drawer 131 and in timed relation to the operation of the header with which the wire drawer is being used.

The cylinder device 133 comprises a double acting cylinder 145 which has one end pivotally connected with a mounting bracket 146 provided on the frame of the drawer 131 by means of a pivot pin 147. A piston 148 operable in the cylinder 145 is connected with a piston rod 149 which is provided at its outer end with a yoke 150.

The piston 148 of the cylinder device 133 is connected with the wedge member 97 of the grip mechanism 130 by linkage which includes a swingable lever 151 having the lower end thereof pivotally connected with the yoke 150 by a pivot pin 152. The lever 151 is swingably supported in a bracket 153 by a pivot pin 154. The upper end of the lever 151 is flexibly connected with the outer end of the stem 98 of the movable wedge member 97 of the grip mechanism 130 by means of a link 155.

Pressure fluid is supplied to and exhausted from the ends of the cylinder 145 through conduits 156 and 157 and such pressure fluid is controlled by a solenoid valve device 158. The valve device 158 comprises a valve unit 159 which controls the flow of actuating fluid to and from the ends of the cylinder 145 and is actuated by a solenoid 160 through a swingable lever 161. The energization of the solenoid 160 is controlled by electric circuit means which includes the limit switch 143.

From the construction and arrangement above described for the grip mechanism 130 and the actuating means therefor, it will be seen that the cylinder device 133 will operate to move the wedge member and retain the same in either its grip-producing position or in its

grip-releasing position, and that these movements of the wedge member will be produced in timed relation to the operation of the wire drawer 131 and in timed relation to the header with which the wire drawer is used, by the operation of the limit switch 143 by the rotary cam 142.

From the foregoing detailed description and the accompanying drawings, it will now be readily understood that this invention provides novel grip mechanism for gripping one or more wires and which grip mechanism can be used to advantage with a wire drawer of the kind frequently employed in conjunction with, and in advance of, a cold-header or other fabricating machine. Additionally, it will be seen that the positive actuation of the grip mechanism by movable wedge means embodied therein, provides for gripping and releasing the wire or wires in a predetermined timed relation to the operation of the wire drawer and the operation of the cold-header, such that the need for a feed stop in the header is eliminated. Likewise, it will be seen that the novel grip mechanism utilizes a plurality of grip blocks which depend in number upon the number of wires to be gripped and that the gripping action of all of the blocks of the group is produced simultaneously by the positive actuation of the wedge means.

It will now also be recognized that since longitudinal movements of the grip blocks is prevented, the undesirable effects of a pull-back movement of the wire are eliminated such that a more accurate feeding of the wire is obtainable. Moreover, since the gripping and releasing of the wire by the grip blocks is produced by only a minimum amount of relative lateral or transverse movement thereof, a very small wedge angle can be used such that a heavy gripping force will be developed in response to only a relatively light actuating force applied to the movable wedge member.

Although the novel grip mechanism is disclosed herein as being used in conjunction with a wire drawer, it should be understood that this is by way of example and that this grip mechanism is adaptable to various other uses and mechanisms concerned with the holding or feeding of one or more wires. It should be further understood that although the novel grip mechanism of this invention has been illustrated and described herein to a somewhat detailed extent, the invention is not to be regarded as being limited correspondingly in scope, but includes all changes and modifications coming within the terms of the claims hereof.

Having thus described my invention, I claim:

1. Grip mechanism for gripping a wire or the like comprising, a grip box, a rotatable shaft, a group of blocks in said box and having cooperating grip elements defining wire gripping means between adjacent blocks, said blocks having relative closing movement therebetween in a direction transverse to the axis of said wire, abutments in said box on opposite sides of said group of blocks, wedge means movable in said box substantially in the direction of said axis, said wedge means being disposed between and having camming engagements with one of said abutments and the adjacent block of said group, fluid pressure responsive cylinder means connected with said wedges means for imparting actuating movement thereto, and valve means operable by and in timed relation to the rotation of said shaft and controlling said cylinder means.

2. Grip mechanism as defined in claim 1 in which said valve means is a solenoid valve means, and in which limit switch means responsive to the rotation of said shaft controls said solenoid valve means.

3. Grip mechanism for gripping a wire or the like comprising, a grip box, a rotatable shaft, a group of blocks in said box and having cooperating grip elements defining wire gripping means between adjacent blocks, said blocks having relative closing movement therebetween in a direction transverse to the axis of said wire, means cooperating with said group of blocks for causing said relative closing movement including a wedge member

movable in said grip box, stem means connected with said wedge member and projecting from said box, cam means on said shaft, a pair of first and second swingable levers having adjacent ends in overlapping relation with

5 a clearance space therebetween, the remote end of said first lever being connected with said stem means and the remote end of said second lever being in engagement with said cam means, and spring means cooperating with said adjacent ends such that spring pressure applied to said 10 first lever tends to move said wedge member in a direction to produce said relative closing movement and spring pressure applied to said second lever holds the remote end of the latter against said cam means and yieldingly maintains said clearance space.

15 4. In a grip device for wire or the like, a plurality of relatively movable blocks having cooperating portions defining a through passage and a gripping means for the wire between adjacent blocks, said gripping means being effective to grip the wire in response to a relative closing 20 movement of the blocks, support means supporting said blocks for such relative closing movement, a pair of relatively inclined and relatively movable thrust elements associated with said blocks, said thrust elements being in a spaced-apart relation defining a tapered guideway ex-

25 tending substantially parallel to said through passage, a wedge member reciprocably movable along said guideway for camming cooperation with said thrust elements to produce positive closing movement of said blocks for intermittently gripping said wire during the operation of 30 the grip device, a rotatable shaft, and means for causing the reciprocation of said wedge member comprising spring means acting to move the wedge member in one direction along said guideway and thrust transmitting means effective between said shaft and said wedge member for 35 moving the latter along said guideway in the other direction and in opposition to said spring means.

5. In a grip device for wire or the like, a plurality of relatively movable blocks having cooperating portions defining a through passage and a gripping means for the

40 wire between adjacent blocks, said gripping means being effective to grip the wire in response to a relative closing movement of the blocks, a first spring means tending to cause a relative opening movement of said blocks for releasing the wire, support means supporting said blocks for such relative closing and relative opening movement, a pair of relatively inclined and relatively movable thrust elements associated with said blocks, said thrust elements being in a spaced-apart relation defining a tapered guideway extending substantially parallel to said through passage,

45 a wedge member reciprocably movable along said guideway for camming cooperation with said elements to produce positive closing movement of said blocks for intermittently gripping said wire during the operation of the grip device, a rotatable shaft, and means for causing the reciprocation of said wedge member comprising a second spring means continuously acting to move said wedge member along said guideway in a direction to produce said relative closing movement and thrust transmitting means effective between said shaft and said wedge member for moving the latter along said guideway in the other direction and in opposition to said second spring means.

6. In a grip device for wire or the like, a grip box, a plurality of relatively movable blocks in said grip box and having cooperating portions defining a through passage and a gripping means for the wire between adjacent blocks, said gripping means being effective to grip the wire in response to a relative closing movement of the

50 blocks, a pair of relatively inclined and relatively movable thrust elements in said box and associated with said blocks, said thrust elements being in a spaced-apart relation defining a guideway extending substantially parallel to said through passage, a wedge member reciprocably movable along said guideway for camming cooperation with said thrust elements to produce positive closing

55 movement of said blocks for intermittently gripping said wire during the operation of the grip device, a rotatable shaft, and means for causing the reciprocation of said wedge member comprising a second spring means continuously acting to move said wedge member along said guideway in a direction to produce said relative closing movement and thrust transmitting means effective between said shaft and said wedge member for moving the latter along said guideway in the other direction and in opposition to said second spring means.

70 7. In a grip device for wire or the like, a grip box, a plurality of relatively movable blocks in said grip box and having cooperating portions defining a through passage and a gripping means for the wire between adjacent blocks, said gripping means being effective to grip the wire in response to a relative closing movement of the blocks, a pair of relatively inclined and relatively movable thrust elements in said box and associated with said blocks, said thrust elements being in a spaced-apart relation defining a guideway extending substantially parallel to said through passage, a wedge member reciprocably movable along said guideway for camming cooperation with said thrust elements to produce positive closing

movement of said blocks for intermittently gripping said wire during the operation of the grip device, stem means connected with said wedge member and projecting from said grip box, a spring effective between said grip box and stem means for continuously urging said wedge member along said guideway in a direction to cause the relative closing movement of said blocks, a rotatable shaft, and lever means swingable in response to the rotation of said shaft and engageable with said stem means for imparting movement to said wedge member in the other direction along said guideway and in opposition to said spring.

7. A grip device as defined in claim 6 in which the cooperating engageable portions of said stem means and said lever means have clearance space therebetween for insuring a substantially full actuation of said wedge member by said spring.
